INVENTOR:
HARRY UNGAR,
BY Hugh K. Wagner,
ATTORNEY.

UNITED STATES PATENT OFFICE

HARRY UNGAR, OF ST. LOUIS, MISSOURI, ASSIGNOR, BY MESNE ASSIGNMENTS, TO
DUBLIER CONDENSER CORPORATION, OF NEW YORK, N. Y., A CORPORATION OF
DELAWARE

RADIO CONNECTION

Application filed April 5, 1928. Serial No. 629,956.

This invention relates to radio connections whereby the antenna terminal of a radio set is inductively connected to an electric light socket, thereby utilizing the exterior wires leading to such socket as an aerial and rendering unnecessary the erection of the conventional outside aerial; and has for its object to provide such a device which shall be efficient in operation and simple and compact in construction.

In the accompanying drawings forming part of this specification, in which like number of reference denote like parts wherever they occur,

18 Figure 1 is a perspective view of the device as it appears when disconnected;

Figure 2 is a longitudinal central sectional view taken through the prongs or blades, showing the device connected to an electric 20 socket plug; and

Figure 3 is a transverse sectional view taken on the line 3—3 of Figure 2.

Referring to the drawings, 1 designates a 25 cylindrical body molded of insulating material and having a concentric cylindrical recess 2, a wall 3 surrounding said recess 2, and an annular concentric recess 4, and outer wall 5, and end wall 6 at one end thereof, and an opening 7 at its other end. Imbedded in 30 recess 4 is a metal tube 8, preferably copper, having its upper end terminating in a blade 9, while imbedded in end wall 6 and diametrically opposed to blade 9 is a blade 10, which is dead-ended at 11 in end wall 6. The blades 35 9 and 10 extend through the top 12 of an end wall 6 and have near their ends 13 apertures 14, the ends 13 being beveled at 15 to facilitate their insertion into the openings 16 in plug 17. A tube 18, preferably copper, 40 fits within recess 2 against wall 3, and has connected to its interior, preferably by soldering, the metal strands 19 of an insulated flexible wire or cord 20, which terminates at its other end in a metal tip 21 having a reduced portion 22 for connection to the antenna terminal of a radio set. Wire 20 passes 45 through an opening 23 in a cap 24 molded of insulating material and cemented to the ends 25 and 26 of the walls 3 and 5 for the purpose of closing the opening 7, the end 26 of wall

5 projecting slightly beyond the end 25 of wall 3 and the ends of the metal tubes 8 and 18 for co-operation with an annular depression 27 in cap 24.

Plug 17 forms no part of this invention 55 and may be of any of the usual types, consisting conventionally of an insulating body 28 having the metal prongs or blades 29 and 30 connected to the screw head 31 and screw cap 32 respectively, the prongs 29 and 30 60 having beads or bends 33 for engagement with the apertures 14 of the blades 9 and 10 for the purpose of insuring continued connection of the blades 9 and 10 with the plug 17 after the same has been established. 65

In operation, the plug 17 is screwed into any electric light socket, after which the blades 9 and 10 are connected with plug 17 and the tip 21 is connected to the antenna terminal of the radio set, which is then tuned 70 to the wave length of the desired transmitting station, the set, of course, having the usual ground connection. The radio impulses are collected by the outside wires and pass through the plug 17 and the blade 9 75 to the tube 8, whence they are conveyed by electro-static induction across the wall 3 to the tube 18 and thence by conduction through wire 20 to the antenna terminal of the radio set. It is, of course, understood that no 80 lighting current can flow through this radio connection, since the blade 10 is dead-ended at 11 in insulating wall 6 and blade 9 and tube 8 are insulated from the tube 18 by the wall 3. 85

Having thus described this invention, I hereby reserve the benefit of all changes in form, arrangement, order, or use of parts, as it is evident that many minor changes may be made therein without departing 90 from the spirit of this invention or the scope of the following claims.

I claim:

1. In a radio connection, a member formed of insulating material, a plug attached to 95 said member and adapted for insertion in a lamp socket, said member having concentric recesses leading in from the free end thereof, a tube positioned in the outer recess and having an extension for engaging one ter- 100

5 minal of said plug, a second extension insulated from said tube and adapted for connection with the other of said plug terminals, a second tube positioned in the other recess and being insulated from the first-mentioned tube and means for attaching said second tube to a radio set and subsequent inductive connection to said socket.

2. A connecting device for inductively coupling a high frequency receiving set to a low frequency power line, comprising an enclosing body of insulating material, an armature element in the form of a plate within the body having a portion extending to the outside of the body for engaging an outlet of the power line, another plate of opposite polarity within said body having conducting means for connecting the same with the receiving set, said plate elements being separated and maintained in spaced relation by the insulating material of the body.

3. A connecting device for inductively coupling a high frequency receiving set to a low frequency power line, comprising an enclosing body of insulating material, an armature element in the form of a plate within the body having a portion extending from one end of the body for engaging the outlet of a power line, another plate of opposite polarity within said body having conducting means extending from the opposite end of the body for connecting the same with the receiving set, said plate elements being separated and maintained in spaced relation by the insulating material of the body.

In testimony whereof I hereunto affix my signature.

HARRY UNGAR.
